UNITED STATES PATENT OFFICE.

HERMAN S. HEICHERT, OF FORD CITY, PENNSYLVANIA, ASSIGNOR TO PITTSBURGH PLATE GLASS COMPANY, OF PITTSBURGH, PENNSYLVANIA, A CORPORATION OF PENNSYLVANIA.

DRIER FOR WALL-BOARDS.

1,026,162.

Specification of Letters Patent.

Patented May 14, 1912.

Application filed June 1, 1909. Serial No. 499,598.

To all whom it may concern:

Be it known that I, HERMAN S. HEICHERT, a citizen of the United States, residing at Ford City, in the county of Armstrong and 5 State of Pennsylvania, have invented certain new and useful Improvements in Driers for Wall-Boards, of which the following is a specification.

This improvement has for its object, the 10 provision of an improved means for drying wall board such as is commonly formed from a combination of plaster of Paris, wood fiber, cement, and other like materials, mixed with water and made by means of 15 pressure preferably in what is known as a filter press.

The special object of this present invention in the provision of a drier of this character which will accommodate a large number 20 of boards within a minimum of space and which will effectively cause the drying of the same and at the same time support them while they are being dried, in the position in which they will be least liable 25 to injury, as by warping or distortion such as might be caused if they were handled in the usual way.

The above, as well as such other objects as will hereinafter appear, I attain by means of 30 a construction which I have illustrated in preferred form in the accompanying drawing, wherein—

Figure 1 represents in side elevation an apparatus embodying my improvement;

Figure 2 is an end elevation of a like apparatus;

Figure 3 shows in enlarged view a portion of the carriers and holding mechanism which supports the plaster board;

Figure 4 is a plan view of the apparatus shown in Figure 3, with additional links connected thereto;

Figure 5 indicates a detail of the holding mechanism;

Figure 6 indicates a detail showing the supporting means whereby the weight of the boards is taken as they pass through the oven or drier, and

Figure 7 indicates the means employed for 50 the motion or driving of the continuously moving carrier.

Referring now more particularly to Figure 1, it will be seen that I have therein

shown a kind of oven or drying chamber 8 provided with a carrier or endless chain 55 device 9 composed of a plurality of connected link members and adapted to be moved along through the drying chamber 8 and provided with depending projections or parts 11, the specific construction whereof 60 will be hereinafter more particularly described, such depending projections with the mechanism coöperating therewith forming a means for supporting a plurality of plaster boards 12 in vertical position, by suspending 65 them at their upper edges, in which condition they will dry with the least danger of distortion or warping, and in which by their being held a suitable distance apart, the air which ascends from suitable venti- 70 lating flues 13 at the base of the chamber can pass upward between adjacent boards and more readily remove the moisture. If desired, suitable burners may be provided as indicated at 14, along the base of the 75 chamber, to supply heat for making the drying operation more rapid. The carrier or endless conveyer 9 is carried at each end around a suitable pulley wheel 15 which is shown in detail in Figure 7 and which is 80 provided with notches 16 adapted to receive the ends 17 of the cross bars or rods which in this case are preferably made in tubular form as indicated at 18 in Figure 6, and at their extreme outer ends on the projecting 85 central portions 17 carry the supporting rollers 19 that are held in place by the cotter pins 19' or other suitable contrivance, and are so located as to run along the horizontal track 20 indicated more clearly in Figure 2, 90 and which is preferably formed by means of an angle iron or other suitable commercial rolled shape, there being one below as indicated in Figure 2, and one above the wheel 15. 95

It is obvious that by the provision of the rollers 19 and the cross bars 18 the weight of the plaster board load which is carried by the conveyer is taken by the supporting track or angle bars 20, and the carrier is prevented from sagging, as the strain is taken off the wheel 15 at the end which has the function only of allowing the carrier to turn at the end and progressively drives the same through the instrumentality of the 105 worm wheel 23 driven by the worm shaft

24 which in turn is driven by belt pulley and overhead driving shaft 26 as clearly indicated in Figure 2.

As a means for causing rapid circulation 5 of air through the drying chamber I provide the outlet flue 27 and the fan 28, which latter is driven in turn by the belt 29 from the driving shaft 26.

Referring now more particularly to Figures 3 to 7, it will be seen that the detail 10 construction of the conveyer or carrier apparatus is such as will readily support the plaster boards at their upper edges. Thus the members 10 constituting the links of 15 the carrier or conveyer chain, I provide with downward projections 11 which on one side are plain, as indicated in Figure 3, and on the other side have the inclined or wedge-shaped surfaces 30 adapted to engage with 20 rollers 31 that are mounted upon rods 32, there being for engagement with each board a pair of the rollers 31 coöperating with the two portions of the conveyer which carry one row of boards.

25 It will be evident on examination of Figure 3 that when the board is pushed in and raised into the position shown in said figure it will push the rollers 31 carried by the rods 32 upward until the board passes 30 the rollers, and then as the board comes down the weight of the board and rollers will cause the rollers to roll down on the incline or wedge surface 30 and grip the boards tightly at their upper edges, the 35 wedges 30 being proportioned to secure the requisite degree of pressure laterally to hold the boards from falling out.

It is obvious that in the operation of my invention the boards are introduced at one end of the chamber 8, by pushing them upward between the rollers 31 and the adjacent faces of the depending projections 11, and the movement of the worm shaft 24 causes a continuous travel along through the drier chamber, until at the other end the boards 45 which are dried are removed by any convenient means.

Having thus described my invention and illustrated its use, what I claim as new and desire to secure by Letters Patent, is the 50 following:

1. A conveyer for drying apparatus comprising a plurality of links arranged in pairs, a plurality of arms depending from each link having a flat surface on one side 55 and an inclined rib on the other, and a plurality of rods extending through the pairs of links and supported between the arms by the inclined ribs.

2. A conveyer for drying apparatus comprising a plurality of links arranged oppositely in pairs, a plurality of substantially parallel arms depending from each link provided with inclined faces, a plurality of rods 60 extending between the pairs of links, and rollers on the rods supported between the arms by the said inclined faces.

In testimony whereof I have hereunto signed my name in the presence of the two subscribed witnesses.

HERMAN S. HEICHERT.
